UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

PLUG RECEPTACLE.

Application filed September 2, 1920. Serial No. 407,655.

To all whom it may concern:

Be it known that I, REUBEN B. BENJAMIN, a citizen of the United States, residing at Chicago, in the county of Cook and State of Illinois, have invented new and useful Improvements in Plug Receptacles, of which the following is a full, clear, concise, and exact description, reference being had to the accompanying drawing forming a part of this specification.

My invention relates to electrical connector devices, and more particularly to plug clusters for use with a feed line having a ground return.

One of the objects of my invention is to provide such a connector device which will be durable and efficient in use, simple in construction and easy to assemble.

Further objects will appear from the detailed description to follow and from the appended claims.

In the drawings in which several embodiments of my invention are shown:

Fig. 1 is an axial section of a plug cluster substantially on the line 1—1 of Fig. 2;

Fig. 2 is an elevational view of the plug cluster from the right of Fig. 1, parts being broken away;

Fig. 3 is a part sectional and part elevational view showing a Hubbell type receptacle substituted for one of the Edison receptacles of Fig. 1;

Fig. 4 is a perspective view of the Hubbell type receptacle;

Fig. 5 is a disassociated plan view of the two-part combination housing, supporting and connecting member;

Fig. 6 is a section on line 6—6 of Fig. 1;

Fig. 7 is a part sectional and part elevational view of a different type of plug receptacle; and

Fig. 8 is a part sectional and part elevational view of still another type of plug receptacle.

Referring to Figs. 1 to 6 inclusive, the construction shown comprises in a general way, a plug portion 10, having a threaded shell contact 11, and a center contact 12, for engagement with the corresponding contacts of a receptacle, and a two-way receptacle portion 13, having shell contacts 14, and center contacts 15 for engagement

with the corresponding contacts of a plug-in device. 55

The threaded shell contacts 14 of the receptacle portion are electrically connected with the threaded shell contact 11 of the plug portion, and as the device is used with a ground return in which the threaded shell 60 contact of the outlet is grounded, it is not necessary to provide an insulating housing for the threaded shell contacts 14 of the receptacle portion.

For supporting the contacts and suitably 65 insulating them with respect to each other, a two-part insulating base 16 is provided, comprising a plug base portion 17, for supporting and insulating the plug contacts with respects to each other, and a receptacle 70 base portion 18, for supporting and insulating the receptacle contacts with respect to each other. For holding the two base parts 17 and 18 together, and electrically connecting the plug center contact 12 with the receptacle center contact 15, a central screw 75 19 is provided, which extends through aligned openings in the two base portions, and is threaded into a nut 20, which bears on the base portion of an integral sheet 80 metal stamping, on which the receptacle center contacts 15 are formed.

For mechanically supporting the threaded shell receptacle contacts 14 and electrically connecting them with the threaded shell 85 plug contact, 11, a two-part combination housing, supporting and electrical connector member 21 is provided (Fig. 5) which may be made of sheet metal in two mating halves.

For securing the upper ends of the mating halves 22 of the combination member 21 together, and for securing these mating halves to the threaded shell plug contact 11, each of the mating halves is provided with a lug 23, extending from the flange 95 portion 24, each of these lugs 23 being bent down over the inwardly extending flange 25 of the threaded shell plug contact 11, whereby the mating halves 22 are held together at the upper ends, and electrically 100 and mechanically connected to the threaded shell plug contact 11.

For securing these mating halves together at their lower ends, the threaded shell receptacle contacts 14 are slipped over the 105 semi-cylindrical portions 26 of the members

22, the members 22 and the threaded shell receptacle contacts 14 being provided with a quick-detachable interengaging means for holding the threaded shell contacts in place 5 on the semi-cylindrical portions 26 when they are slipped on. These inter-engaging means may comprise rectangular openings 27 in the semi-cylindrical portions 26 which are engaged by angular lugs 28 struck inwardly from the inner end of the threaded shell receptacle contacts 14. These inwardly struck angular portions 28 act as spring catches for holding the threaded shell contacts in place with respect to the mating halves 22. By means of the connections between the mating halves 22 and the threaded shell plug contact 11 at their upper ends, and the engagement between the lower ends of the mating halves 22 and the threaded shell receptacle contacts 14, the threaded shell plug contact 11, the threaded shell receptacle contact 14, and the mating halves 22 are held together securely in proper relative position. In order to prevent the edges 25 of the mating halves 22 from slipping past each other they are provided with a small flattened portion 29, the flattened portion 29 of one of the mating halves engaging the flattened portion of the other mating half, 30 to prevent the edge of one from slipping past the other.

In order to hold the base parts 17 and 18 in their proper relative position, the base part 17 is provided with a transversely extending recess 30, into which extends the transverse rib 31 on the base part 18.

The circuit is from the center contact 11 through the central screw 19, receptacle center contact 15, translating device, threaded shell receptacle contact 14, combination member 21, and threaded shell plug contact 16 to the ground return.

In Figs. 3 and 4 I have shown a Hubbell type receptacle member which can be substituted for one of the threaded shell receptacle contacts 14, in such a way that its contact will be electrically connected with the proper contact of the plug portion. This receptacle member 32 comprises in a general 45 way two contact members 33 and 34, for engagement with the blades of a separable attachment plug cap, and electrically connected as hereinafter described with the threaded shell plug contact 11 and center plug contact 12, an insulating base 35 for supporting the contacts 33 and 34 and insulating them with respect to each other, and a combination housing and electrical and mechanical connector member 36, surrounding the insulating base 35, and having a quick-detachable connection with respect to the combination housing and connecting device 21.

In order to effect a mechanical connection 55 between the receptacle member 32 and the

combination member 21, the housing member 36 may be provided with an angular spring lug (not shown) similar to the lug 28 previously described, for engagement with one of the rectangular openings 27. In 70 order to electrically connect the contact device 34 with the plug center contact 12, a contact member 37 is provided, secured to the insulating base 35, this member 37 serving also to mechanically hold the base portion of the contact device 34 in place in the insulating base 35. This contact member 37 engages one of the center receptacle contacts 15 and is thus connected with the plug center contact 12 through the central screw 19.

In order to electrically connect the contact device 33 with the threaded shell plug contact 11, the contact device 33 is provided with a spring tongue portion 38, which engages inside the member 21 and is, by means of this member 21, electrically connected with the threaded shell plug contact 11. For securing the contact device 33 in place on the insulating base 35, a rivet member 39 is provided, which extends through registering openings in the insulating base 35 and contact device 33.

The contact devices 33 and 34 are located in recesses 40 and 41 in the insulating base 35, the base 35 being provided with restricted openings 42 and 43 through which the blades of the cap of a separable attachment plug may be inserted for engagement with the contact devices 33 and 34.

In this device the circuit is from the center contact 11 through the central screw 19, receptacle contact 15, contact member 37, contact device 34, translating device, contact member 33, member 21 and threaded shell plug contact 11 to the ground return.

The construction shown in Fig. 7 is substantially the same as that shown in Fig. 3 with respect to the plug portion 10, central screw 19, threaded shell receptacle contact portion 14, and Hubbell receptacle portion 32, the principal difference being in that the threaded shell receptacle contact 14 is in alignment with the plug portion 10, and the Hubbell receptacle portion 32 extends at right angles to the plug portion 10. This necessitates certain changes in the construction of the receptacle base part 44, in the receptacle center contact member 45, and in the combination connecting, supporting 115 and housing member 46.

The receptacle center contact 45 comprises a center contact portion 47 for cooperation with the threaded shell contact 14, and a center contact portion 48 for engagement with the contact member 37 of the Hubbell receptacle 32. The combination member 46 is made in mating halves as in the corresponding member of the form previously described, and is electrically connected to 130

the plug shell contact 11, the receptacle shell contact 14, and the Hubbell receptacle device 32, substantially as in the form previously described, the circuit also being substantially the same as in the form previously described.

The construction shown in Fig. 8 may be substantially the same as the construction shown in Fig. 1 with respect to the plug portion 10, the central screw 19 and the threaded shell receptacle contacts 14, the principal difference being in that the threaded shell receptacle contacts 14 are in alignment with each other, and extend at right angles with respect to the plug portion 10. This construction necessitates changes in the receptacle insulating base portion 49, in the receptacle center contact member 50, and in the combination housing, supporting and electrical and mechanical connecting member 51. The center contact member 50 is provided with a base portion held underneath the nut 20, and with center contact portions 52 for cooperation with the threaded shell receptacle contact 14. The connecting member 51 is made in mating halves and is secured to the threaded shell plug contact 11 and to the threaded shell receptacle contacts 14 in substantially the same manner as the corresponding part in the construction shown in Fig. 1, the circuit also being substantially the same as in the form shown in Fig. 1.

Having thus described my invention, what I claim as new and desire to secure by Letters Patent is:

1. A plug receptacle for use with a ground return system, comprising a plug portion and a receptacle portion, the plug portion comprising a center contact, and a threaded shell contact for electrical connection with the ground return, the receptacle portion comprising a plurality of pairs of receptacle contacts, and a combination housing, supporting, and electrical connector member for housing receptacle portions, and supporting, and electrically connecting with the plug shell contact one of each pair of the receptacle contacts, said combination member comprising two mating halves separable on an axial plane through the plug portion.

2. A plug receptacle for use with a ground return system comprising a plug portion and a receptacle portion, the plug portion comprising a center contact, and a threaded shell contact for electrical connection with the ground return, the receptacle portion comprising a plurality of pairs of receptacle contacts, and a combination housing, supporting and electrical connector member for housing receptacle portions, and supporting, and electrically connecting with the plug shell contact one of each pair of the receptacle contacts, said com-

bination member comprising two mating halves separable on an axial plane through the plug portion, said mating halves being held in their proper relative position by one of said receptacle contacts. 70

3. A plug receptacle for use with a ground return system, comprising a plug portion and a receptacle portion, the plug portion comprising a center contact, and a shell contact for electrical connection with the ground return, the receptacle portion comprising a plurality of pairs of receptacle contacts, and a combination housing, supporting an electrical connector member for housing receptacle portions, and supporting, 80 and electrically connecting with the plug shell contact one of each pair of the receptacle contacts, said combination member comprising two mating halves separable on an axial plane through the plug portion, 85 said mating halves being held together by the shell contact of the plug portion.

4. A plug receptacle for use with a ground return system, comprising a plug portion and a receptacle portion, the plug portion comprising a center contact, and a shell contact for electrical connection with the ground return, the receptacle portion comprising a plurality of pairs of receptacle contacts, one of which pairs includes a threaded shell contact, and a combination housing, supporting an electrical connector member for housing receptacle portions, and supporting and electrically connecting with the plug shell contact one of each pair of receptacle contacts, said combination member comprising two mating halves separable on an axial plane through the plug portion, 95 said mating halves being held together by the threaded shell contact of the receptacle portion. 100

5. A plug receptacle for use with a ground return system, comprising a plug portion and a receptacle portion, the plug portion comprising a center contact, and a shell contact for electrical connection with the ground return, the receptacle portion comprising a plurality of pairs of receptacle contacts, and a combination housing, supporting an electrical connector member for housing receptacle portions, and supporting, 110 and electrically connecting with the plug shell contact one of each pair of receptacle contacts, said combination member comprising two mating halves separable on an axial plane through the plug portion, 115 said mating halves being held together by the shell contact of the plug portion and by one of the receptacle contacts.

6. A plug receptacle for a ground return system, the plug portion comprising a center contact and a threaded shell contact for electrical connection with the ground return, the receptacle portion comprising two cylindrical receptacle members, and a com- 125 130

- combination housing, supporting and electrical connector member for supporting said cylindrical receptacle members, housing the receptacle portions, and electrically connecting said certain receptacle contacts with the threaded shell plug contact, said combination member comprising two mating halves separable on an axial plane through said plug portion, said cylindrical receptacle members and said threaded shell plug contact having provisions for holding together said mating halves.
7. A plug receptacle for a ground return system, comprising a center contact and a threaded shell contact for electrical connection with the ground return, the receptacle portion comprising two cylindrical receptacle members, and a combination housing, supporting and electrical connector member for supporting said cylindrical receptacle members, housing receptacle parts and electrically connecting said cylindrical receptacle members with said threaded shell portions, and electrically connecting certain receptacle contacts with the threaded shell comprising two mating halves separable along an axial plane through the plug portion, plug contacts, said combination member comprising two mating halves separable on an axial plane through said plug portion, said threaded shell plug contact having an inwardly extending flange, and said mating halves having inwardly extending flanges engaging said flange, and having portions bent over said flange to hold said mating halves together.
8. A plug receptacle for use with a ground return system, comprising a plug portion and a receptacle portion, said plug portion comprising a center contact, a threaded shell contact for electrical connection with a ground return, and an insulating base for insulating and supporting said contacts with respect to each other, said receptacle portion comprising two cylindrical receptacle members, and a combination housing, supporting and electrical connector member for supporting said receptacle members, housing parts of the receptacle, and electrically connecting said cylindrical receptacle member with said threaded shell plug contact, receptacle contacts, and an insulating base for supporting said receptacle contacts, said combination member having a flange portion held in place between said two bases.
9. A plug receptacle for use with a ground return system, comprising a plug portion and a receptacle portion, said plug portion comprising a center contact, a threaded shell contact for electrical connection with a ground return, and an insulating base for insulating and supporting said contacts with respect to each other, said receptacle portion comprising two cylindrical receptacle members, and a combination housing, supporting and electrical connector member for supporting said receptacle portions, housing parts of the receptacle, and electrically connecting said combination member having a flange portion held in place between said two bases, said threaded shell plug contact, receptacle contacts, and an insulating base for supporting said receptacle contacts, said combination member having a flange portion held in place between said two bases, said threaded shell plug contact also having a flange held between said bases.
10. A plug receptacle for use with a ground return circuit, comprising a plug portion and a receptacle portion, said plug portion comprising a center contact and a threaded shell contact for electrical connection with the ground return, said receptacle portion comprising two cylindrical receptacle members, and a combination housing, supporting and electrical connector member for supporting said cylindrical receptacle members, housing receptacle parts and electrically connecting said cylindrical receptacle members with said threaded shell plug contact, said combination member comprising two mating halves separable along an axial plane through the plug portion, and means for effecting the quick-detachable engagement of said cylindrical members with respect to said combination member.
11. A plug receptacle for use with a ground return circuit, comprising a plug portion and a receptacle portion, said plug portion comprising a center contact and a threaded shell contact for electrical connection with the ground return, said receptacle portion comprising two cylindrical receptacle members, and a combination housing, supporting and electrical connector member for supporting said cylindrical receptacle members, housing receptacle parts and electrically connecting said cylindrical receptacle members with said threaded shell plug contact, said combination member comprising two mating halves separable along an axial plane through the plug portion, said cylindrical members having a quick-detachable engagement with respect to said combination member, one of said cylindrical receptacle members being provided with contacts for engagement with the blades of an attachment plug cap.
12. A plug receptacle for use with a ground return circuit, comprising a plug portion having a center contact and a threaded shell contact for electrical connection with a ground return, said receptacle portion comprising two center contact members, a threaded shell contact having means for effecting a quick-detachable engagement with respect to said receptacle portion, and a cylindrical receptacle portion having contacts for engagement with the contacts of a cap of a separable attachment plug, one of the contacts of said cylindrical receptacle portion being electrically connected with one of the receptacle center contacts, said cylindrical receptacle member having a

quick-detachable engagement with respect to said plug receptacle.

13. A plug receptacle comprising a plug portion for engagement with a socket and a receptacle portion having means for quick-detachable connection with a threaded shell receptacle contact, and having a center contact, and a cylindrical receptacle portion having contacts for engagement with the contacts of the cap of a separable attachment plug, having a quick-detachable engagement with said plug receptacle contact, and having one of its contacts electrically connected with said center contact.

14. A plug receptacle comprising a plug portion, and a receptacle portion, said receptacle portion having a center contact, and a cylindrical receptacle member having contacts for engagement with the blades of a separable attachment plug cap, said cylindrical receptacle member having means for effecting a quick-detachable engagement with respect to said plug receptacle, one of its contacts being electrically connected with said center contact.

In witness whereof, I have hereunto subscribed my name.

REUBEN B. BENJAMIN.
